UNITED STATES PATENT OFFICE.

GRANT BURTON, OF DUNCANVILLE, ALABAMA

TURPENTINE-STILL.

1,293,027.

Specification of Letters Patent.

Patented Feb. 4, 1919.

Application filed November 17, 1917. Serial No. 202,491.

To all whom it may concern:

Be it known that I, GRANT BURTON, a citizen of the United States, residing at Duncanville, in the county of Tuscaloosa and State of Alabama, have invented certain new and useful Improvements in Turpentine-Stills, of which the following is a specification.

This invention has relation to turpentine stills and has for an object to provide an apparatus for use in connection with a turpentine still whereby the turpentine may be separated from the water and other substances which distil over from the raw material.

Another object of the invention is to provide means in a turpentine still for indicating the height of the material within the still and for warning the distiller when the contents of the still are boiling too rapidly thereby preventing any of the solid matter from going over into the condensing apparatus.

Another object of the invention is to provide an apparatus for use in connection with a turpentine still whereby when the turpentine is being distilled, the turpentine may be collected in one vessel and the water separated therefrom and conducted to a second vessel, said means being operable to prevent any entrance of water into the first mentioned vessel when the charge of the still is about exhausted at which time only water will be distilled.

A still further object of the invention is to provide an automatically operable means for placing receivers beneath the outlet of the still whereby to receive the turpentine therein and subject the same to a final separating process, said means being operable to place one container after another beneath the outlet as the containers become filled.

A still further object of the invention is to provide means for operating the turpentine receiving means mentioned in the preceding paragraph, said means being operable by the weight of the water collected in a vessel from the condenser of the turpentine still.

In addition to the foregoing my invention comprehends improvements in the details of construction and arrangement of the parts to be hereinafter more fully described and particularly set forth in the appended claims.

In the accompanying drawings in which

similar and corresponding parts are designated by the same characters of reference throughout the several views in which they appear:

60

Figure 1, is a diagrammatic view in side elevation of a turpentine still illustrating the embodiment therein of my improved separating apparatus.

Fig. 2, is a section on the line 2—2 of the preceding figure.

Fig. 3, is a view in section taken along the line 3—3 of Fig. 1.

Fig. 4, is a detail view in section of two of the separating elements of my apparatus.

70

Fig. 5, is a view in section of the vessels containing the alarm and still gaging apparatus.

Fig. 6, is a view in section taken at right angles to the section of the preceding figure, and

75

Fig. 7, is a detail view in section taken on the line 7—7 of Fig. 1.

With reference to the drawings 10 indicates a turpentine still of conventional type 80 mounted in a furnace 11 and having an outlet 12 at its upper portion leading to a worm condenser 13 of conventional type, the outlet of the worm being indicated at 14.

85

An opening is formed in the upper portion of the still over which opening is clamped a device indicated generally at 15 which comprises an alarm mechanism and means for suspending a float within the still. This device comprises a bottom plate 16 90 from which depends a pair of spaced rods 17 between which a float 18 is suspended, said float being movable vertically and guided by said rods. The device 15 comprises a hollow enlarged portion 19 having 95 a gong 20 secured to the outer side thereof with a hammer 21 adapted to engage the gong, pivoted interiorly of the enlarged portion 19 at 22, and having a bifurcated portion at 23 through which bifurcated portion 100 a flexible element or cord 24 passes. The lower end of the cord is attached to the float 18, the cord thence passing around a pulley 25 mounted in a pipe 26 in communication at one end with the upper portion of the 105 enlarged portion 19 of the device 15, said cord extending horizontally from said pulley 25 and passing around a pulley 27 located in a cylindrical casing 28 disposed some distance away from the still. The opposite end of the flexible element 24 is then connected to the upper end of a second flexi-

105

110

ble element 29 provided within the casing 28, said flexible element 29 passing over a pulley 30 within the casing and having at its opposite or lower end connected thereto 5 a pointer 31 movable vertically upon a guide rod 32, the point of connection of the flexible elements 24 and 29 having connected thereto a weight 33 whereby the pointer 31 is urged toward an upward position. The 10 weight 33, however, being overbalanced by the weight of the float within the still. A scale 34 may be placed within the casing 28 in proximity to the pointer and an opening may be provided in the casing whereby the 15 proximity of the pointer to any of the graduations on the scale may be observed.

From the foregoing description it will be obvious that the level of the fluid within the still may be known constantly by observing 20 the height of the pointer 31 within the casing 28, and furthermore as the contents of the still rise, as it frequently does, this fact may be known to the distiller who can then lower the heat to prevent boiling over 25 of the still.

As is well known in this art, considerable amount of water is distilled over with the turpentine, and the problem is therefore to separate the water from the turpentine, in 30 as convenient and efficient a manner as possible. To this end I have provided a series of apparatus, beginning with a preliminary separating apparatus indicated in Fig. 1 of the drawings. This comprises a vertically disposed cylindrical tank 36 in the upper end of which the outlet 14 of the worm 13 projects. These elements are set forth in detail in Fig. 4 from which it will be noted that pulley 39 is mounted in a bracket depending from the top portion of the tank 36, a flexible element 40 passing around said pulley and having at one end a float 41 with the opposite end connected to the lever 42 of a valve 43. The valve 43 is interposed in a pipe 44 having its open end within the casing 36 disposed at a predetermined point, a coil spring 45 having one end secured to the handle 42 and the opposite end to the interior of the casing acting 50 to normally retain said valve in a closed position. The float 41 is preferably of the type comprising a hollow air tight body having relatively thin walls and should have buoyancy sufficient to permit it to float upon 55 water but to sink in turpentine.

A pipe 46 is connected at one end to the lower end of the casing 36 with the opposite end of the pipe leading into the upper portion of a horizontally disposed cylindrical 60 casing 47 located adjacent the casing 36, with the end of the pipe 46 extending within the casing to a point adjacent the bottom thereof as indicated in Fig. 4 of the drawings. The pipe 46 is formed with an upwardly extending, inverted U-shaped bent

portion 46, extending to a point above the pipe 44 and on a level with the valve 43. The lower end of said pipe 46 is preferably placed adjacent the outlet pipe 48 of the casing 47 for a purpose which will be presently obvious. The pipe 44 mentioned above extends from the casing 36 into the casing 47 at a point opposite the point of introduction of the pipe 46 and is designed to discharge into a cup 49 mounted on one 75 end of a lever 50, fulcrumed at 51 within the tank, and having its opposite end connected through the medium of a link 52 to a valve 53 which controls the opening of a depending turpentine discharge pipe 54. 80 The cup 49 is provided with a greatly constricted opening 49' and the lever 50 should be balanced so as to permit the valve 53 to remain in closed position when the cup 49 is empty. 85

The outlet pipe 54 of the vessel 47 discharges into a bucket 55 which is pivotally mounted upon one end of a lever 56, fulcrumed at 57 and having its other end provided with a weight 58 to overbalance the 90 weight of the bucket and to elevate the bucket when the same is emptied. The bucket 55 is normally disposed about a tank 59 provided with an outlet pipe 60 which is connected to an opening located adjacent the upper end 95 of the tank. An outlet opening is also formed adjacent the lower end of the tank and a pipe 61 is connected thereto having a joint 62 secured thereto and the branch pipe 63 extending from said joint. A flexible 100 element 64 connects the branch 63 of the pipe with the weighted end of the lever 56 whereby the branch 63 is retained in an elevated position so as to dispose the upper end of the branch above the normal level of 105 fluid within the tank 59 when the bucket 55 is depressed. The bucket 55 is provided in its bottom with a restricted opening to permit the contents thereof to flow slowly therefrom. 110

A turntable 65 is mounted to rotate in a horizontal plane beneath the outlet pipe 60 of the tank 59, said turn table being mounted upon the shaft 66 having a bevel gear 67 secured thereto for meshing engagement 115 with the bevel gear 68 mounted upon a horizontal shaft 69. The shaft 69 also supports a wheel 70 having a plurality of radial arms 71, each arm carrying a bucket 72 at its outer end. A trough 73 is provided having 120 its discharge end located above the bucket 72 so as to discharge thereinto one bucket at a time, the other end of the trough being located so as to receive the contents of the tank 59 when the branch 63 of the pipe 61 125 is lowered to discharge into said trough.

The turn-table 65 carries a plurality of tanks 74 in uniformly spaced relation each tank having an outlet pipe 75 connected to an opening in the lower end of the tank, said 130

outlet pipe being rotatably mounted therein and normally extended upwardly so as to dispose the upper end thereof at a point above the normal level of the fluid within the tank so as to retain the contents of the tank therein until the said pipe 75 is moved downward to permit the discharge of the tank contents. A rod 76 extends vertically and is mounted in guides exterior of each of the tanks 74. The upper end of the rod is directed into the tank and is provided with a float 77 to float on water and sink in turpentine. The lower end of the rod 76 is then bent at right angles as at 78 for engagement with the stop. A bracket 79 is mounted adjacent the periphery of the turn-table and is formed with a vertically extending slot 80 in which a block 81 slides. The block is adapted to be positioned so as to be engaged by the out-turned end 78 of the rod 76 when the float 77 is in a depressed position, but to clear said stop when the float is elevated, or when the block 81, is in the lower end of the slot 80.

The outlet of the tank 47 is connected to a pipe 48 which terminates at a point to discharge into a bucket 82 which is mounted on one end of the lever 83 pivoted as at 84. The opposite end of the lever 83 carries a weight 85 whereby to overbalance the weight of the bucket 82 when the bucket is empty. The weighted end of the lever 83 is connected to the block 81 whereby the block may be elevated when the bucket 82 is depressed. The bucket 82 is normally suspended over a tank 86 having an outlet pipe 87 connected to a point adjacent the lower end thereof and an outlet pipe 88 connected to an opening located adjacent the upper end.

The construction of my apparatus having been set forth above in detail its operation may be briefly stated as follows:

The products of condensation from the worm 13 are led into the chamber 36. The chamber 36 also provides for a preliminary separation of the turpentine and water, the turpentine being of a lesser specific gravity, floats upon the surface of the water, as long as the level of the water is below the upper end of the pipe 44 the valve 43 will be retained in open position since the float 41 will sink in the turpentine. As the level of the water in the chamber 36 rises, the float 41 is carried upward thereby permitting the tension of the spring 45 to relax so as to move the valve 43 to closed position. This movement toward a closed position will however not take place until the float 41 has risen sufficiently or until the level of the water reaches the mouth of the pipe 44 within the chamber. Prior to this however, turpentine will flow into the pipe 44 and into the cup 49 of the container 47, rapidly filling the cup so as to cause the same to move

downward and raise the valve 53. As a result the contents of the container 47 will flow out through the pipe 54, and as long as the cup 49 is depressed, water from the chamber 36 as well as turpentine flowing from the pipe 44 will flow from the vessel 47 out through the pipe 54, and as long as the cup 49 is depressed, water from the chamber 36 as well as turpentine flowing from the pipe 44 will flow from the vessel 47 out through the pipe 54 into the receptacle 55 which happens to be disposed beneath the discharge end of said pipe 54. It is to be noted at this time that if only water is being condensed in the worm, it will pass out through the pipe 46 about as fast as it enters the chamber 36, and will therefore pass into the container 47 and effect an exit therefrom through the pipe 48. In this manner, no fluid is permitted to discharge through the pipe 54 unless accompanied by the slightest quantity of turpentine. As long as turpentine is condensed the bucket 55 will be held in a depressed position and the branch 63 of the pipe 61 will be retained in an elevated position to retain the contents of the tank 59 therein. As the tank 59 becomes filled and the level of the turpentine reaches the opening to which the outlet pipe 60 is connected. The turpentine flows through the pipe 60 and is caught in one of the tanks 74 mounted upon the turntable. As the tank 74 gradually fills, the float 77 is raised until the lower end of the rod 76 is elevated so as to clear the top of the block 81. When the charge in the still is exhausted and turpentine no longer passes through the apparatus, the contents of the bucket 55 will eventually escape through the constricted opening thereof whereby the bucket will be elevated by the depression of the weighted end of the lever 83, the downward movement of said weighted end of the lever permitting the branch 63 of the pipe 61 to also descend and to discharge the water contained in the tank 59 into the trough 73 by which the water is directed into the bucket 72 of the water wheel 70 to rotate said wheel. Rotation of the water wheel 70 thus produced is transmitted through the shaft 69, gears 67 and 68 to the shaft 66 thereby rotating the turntable so as to remove the filled tank 74 from beneath the discharge spout 60 and to substitute an empty tank, the movement of the turntable being limited by the engagement of the rods 76 of the empty tank with the stop block 81, so as to position the empty tank in a position to be filled. During the passage of fluid of any character through the condenser, either water or turpentine the bucket 82 will be constantly filled and as a consequence the block 82 will be retained in an elevated position for engagement by the depressed rod 76 of the tank 74 of the turn table. When

the still is no longer discharging vapor products and the bucket 82 becomes emptied of its contents the weight 85 will act to raise the bucket and the block 81 will be lowered 5 and the turntable 65 permitted to rotate freely for the purpose of bringing the next tank 74 into a position to be filled. It will be noted that in the next adjacent empty tank the float 77 will be lower and hence the 10 lower end of the rod 76 will engage the block 81, even in the lowered position of said block with the result that the turntable is properly positioned to bring the tank 74 beneath the pipe 60. The buckets 55 and 82 15 will empty at the same time so that the lowering of the pipe 63 and the consequent operation of the turn-table will take place simultaneously with the lowering of the blade 81 to permit the turn-table to rotate. 20 The turntable will be held against rotation because the float 77 in the tank 74 will not float high enough to release the turntable. The entire apparatus with the exception of the still and condenser should be inclosed 25 in a housing and the same locked to prevent tampering of the stiller with the apparatus, the key being in charge of an authorized person. A valve controlled pipe 13' is led from the condenser to supply cold water to 30 the tank 86 to cool the turpentine.

Thus it will be seen that I have provided an apparatus for distilling turpentine, whereby the act of separating turpentine from the water takes place automatically, 35 and whereby the product of the still may be tested at times to determine the quality of the product and the extent of dilution thereof with water.

While I have illustrated and described my 40 invention with some degree of particularity, I realize that in practice various alterations thereover may be made, and I therefore desire to reserve the right and privilege of changing the form of the details of construction, or otherwise altering the arrangement 45 of the correlative parts without departing from the spirit of the invention or the scope of the appended claims.

Having thus described my invention what 50 I claim as new and desire to secure by Letters Patent is;

1. In a turpentine still, the combination 55 of a container for receiving the distillate, a second container for receiving the distillate from the first, an upwardly bent pipe connection between the lower end of the first container and the upper portion of the second, a normally open discharge opening, and a normally closed valve controlled 60 discharge opening for said second container, and means in said second container operable when turpentine is received therein to open the valve controlled discharge to permit discharge of the turpentine, said valve controlled opening remaining closed when water 65

alone passes into the second container whereby said water is discharged through the normally open discharge.

2. In a turpentine still the combination 70 of a container for receiving the distillate, a second container for receiving the distillate from the first, an upwardly bent pipe connection between the lower end of the first container and the upper portion of the second, a normally open discharge for said 75 second container, a second discharge for said second container, a normally closed valve for said second discharge, a pipe connecting the first container with the second whereby to convey turpentine from the first container to 80 the second, a second pipe for conveying water from the first container to the second, said water discharging from the normally open discharge, and means in the second 85 container operable when turpentine is received therein from the first mentioned pipe for opening the valve to permit discharge of said turpentine and water through the second discharge opening.

3. In a turpentine still the combination 90 of a container for receiving the distillate, a second container for receiving the distillate from the first, an upwardly bent pipe connection between the lower end of the first container and the upper portion of the second, a 95 normally open discharge opening in the second container, a normally closed discharge opening in the second container, a valve for closing said opening, a lever fulcrumed within the container and having 100 one end connected to the valve, a cup provided upon the opposite end of the arm, said cup having a constricted aperture, a pipe leading from the upper portion of the first container into the second container for 105 discharging the cup, and a second pipe leading from the lower portion of the first container into the second container adjacent the normally open discharge thereof whereby when turpentine is received from the 110 first container, the cup may be filled and depressed to open the valve to permit discharge of turpentine from the second container, said valve remaining closed when only water is received in the second container, whereby said water may discharge 115 through the normally open discharge.

4. In a turpentine still, the combination 120 of a container for receiving distillate, a second container for receiving the distillate from the first, a pipe leading from the upper portion of the first container into the second, a valve in said pipe, means for retaining the valve in normally closed position, a float within the first container, means operable 125 by the float when raised for opening the valve to permit discharge of turpentine from the container through the pipe, a second pipe for discharging water from the lower portion of the first container into the 130

- second container, an upwardly extending bent portion in said second pipe extending above the first pipe, said second container having a normally open discharge opening, 5 and a normally closed valve controlled discharge, and means operable when turpentine is received into the second vessel for opening said valve to permit the discharge of turpentine therefrom, said valve remaining closed when only water is received from the first container to cause said water to be discharged from the normally open discharge of the second container.
- 10 5. In a turpentine still the combination of a container for receiving the distillate, a second container for receiving the distillate from the first, a pipe extending from the upper portion of the first container into the second container, a valve interposing said pipe and located within the container, a handle for operating said valve, resilient means engaging the handle for normally retaining the valve in open position, a pulley within the container, a flexible ele-
- ment connected at one end to the arm, extending over the pulley and having a float secured to its opposite end whereby when the float rises, the valve may be moved to closed position, a second pipe leading from the lower portion of the first container into the second, an upwardly extending bent portion in said second pipe extending above the first pipe, a normally open discharge for said second container and a normally closed valve control discharge, and means operable when turpentine is received into the second container for opening the valve to permit the discharge thereof, said valve remaining closed when water only is received in the second container whereby its discharge is caused to take place through the normally open discharge.
- 15 In testimony whereof I affix my signature in presence of two witnesses.
